P. JANTZEN

TROUSER CUFF SUPPORT

Filed May 17, 1927

INVENTOR.

PAUL JANTZEN.

BY *Marvin Palmer*
ATTORNEY.

UNITED STATES PATENT OFFICE.

PAUL JANTZEN, OF NEWARK, NEW JERSEY.

TROUSER-CUFF SUPPORT.

Application filed May 17, 1927. Serial No. 192,003.

This invention relates to supports and more particularly to such devices as are used to keep portions of wearing apparel in their proper shape.

For instance, in the case of trousers; if a wearer happens to be out in the rain or snow, the cloth will lose its shape, particularly the cuff portion.

Such occurrence necessitates pressing which, if repeated very often, is expensive and harmful to the cloth.

It is therefore the main object of this invention to provide means readily and quickly adapted to the cuffs of trousers to cause the same to maintain their shape.

A further object is in the provision of an exceedingly simple and cheap device that is adjustable to any desired size, making the same interchangeable from one cuff to another.

These objects and others, which will become apparent as the description progresses, are accomplished by the novel construction, combination and arrangement of few and simple parts, hereinafter described and illustrated in the accompanying drawing, forming an important component of this disclosure, and in which:

Figure 1 is a fragmentary side elevational view of a pair of conventional trousers equipped with the preferred embodiment of this invention.

Figure 2 is a transverse sectional view taken on line 2—2 of Figure 1, drawn to an enlarged scale.

Figure 3 is a similar view taken on line 3—3 of Figure 2 but with the trouser cuff omitted.

Figure 4 is a fragmentary plan view of the adjustable element of the device.

Figure 5 is a like view of the mating element of the member shown in Figure 4.

Figure 6 is a fragmentary, longitudinal sectional view showing a modified form of support.

Figure 7 is a plan view of the connecting member used in the modification.

Figure 8 is a transverse sectional view taken on line 8—8 of Figure 6.

Figure 9 is an edge view showing a modified form of the appliance.

In the drawing, the numeral 10 generally

designates the leg portion of a pair of trousers having the usual outwardly turned cuff 11.

In Figures 1 to 5 inclusive, a U-shaped member 12, made of flat, resilient metal, is provided at its ends with a series of perforations 13, the adjacent edges of the strip being bent to present channels 14.

Slidable in the channels are the ends of similar strips 15, oppositely disposed to the element 12 and adjustable therein by a plurality of detents 16 engageable with the perforations 13, best seen in Figure 3.

Thus, the strips 12 are placed in the cuffs of a pair of trousers and the members 15 engaged therewith to keep the cuffs in their proper shape.

It will be noted that the supports are adjustable so that the same may be interchangeable from one pair of trousers to another.

In the modification shown in Figures 6 to 8 inclusive, a channel member 20 is provided on its back with inreaching detents 21 engageable with similar detents 22 formed on the ends of U-shaped strip 23 fast in the channel 20.

Slidable in the channel from the opposite end of the strip 23 is a similar strip 24 adjustably engageable with the detents 22 through a series of openings 25.

The modified form of support is used in the same manner as the preferred and it will be noted that by the use of these articles, trousers will be kept in proper shape for a longer period of time than before, thus materially reducing the cost of pressing, etc.

In Figure 9 a single bend is shown, the same having a central row of indentations on its outer side to produce protuberances 26, the same being engageable with corresponding indentations which are held in adjusted relation by a clasp 27 confining the ends of the strip 28 in an obvious manner.

While only the preferred forms of my invention have been shown and described, it is to be understood that changes may be made in size, proportion, etc., without the exercise of invention or departing from the scope of the appended claim.

Having thus described my invention,

what I claim as new and desire to secure by Letters Patent, is:—

A trouser cuff support comprising a pair of opposed U-shaped strips, one of said strips having a series of perforations in its ends, detents on the other of said strips engageable with the openings, a separate

channel member encasing the engaged ends, and detents on said channel member engageable with the detents of said second strip. 10

In witness whereof I have affixed my signature.

PAUL JANTZEN.
